UNITED STATES PATENT OFFICE.

LUTHER C. CROWELL, OF BROOKLYN, ASSIGNOR TO R. HOE & CO., OF NEW YORK, N. Y.

SHEET FEEDING AND REGISTERING APPARATUS.

SPECIFICATION forming part of Letters Patent No. 278,777, dated June 5, 1883.

Application filed May 20, 1881. (No model.)

To all whom it may concern:

Be it known that I, LUTHER C. CROWELL, a citizen of the United States, residing in the city of Brooklyn, county of Kings, and State of New York, have invented certain new and useful Improvements in Sheet Feeding and Registering Apparatus, fully described and represented in the following specification and the accompanying drawings, forming a part of the same.

In the operation of printing sheets of paper, and especially in printing the blank side of a previously-printed sheet, which latter sheets are necessarily fed a second time to the printing mechanisms, as well as in feeding printed sheets as supplements to mechanisms co-operating with printing mechanisms to deliver the sheets, so that a sheet just printed may have a previously-printed supplement properly combined with it, the greatest feeding accuracy is required. This is accomplished in hand-fed machines by means of a variety of gages, sometimes by register-points, and in some instances by pneumatic apparatus. In web-printing machines, however, where the long lengths of material are printed at very high speed, the sheets are produced by transverse severing of the web after the same has been printed, and the register of impressions on opposite sides of the web is secured before the web is divided to form the sheets. In the present state of the art of rapid printing, more particularly that known as "newspaper-printing," now generally performed by rotary printing-machines, in which a long length of paper wound up in the form of a roll is fed through the mechanisms, printed upon both surfaces, and cut transversely through the margins to form the sheets, said sheets are either gathered into pairs, triplets, &c., to constitute a whole product, or the component sheets of the latter are simultaneously folded together, or otherwise delivered in their collected condition, or each successive sheet is folded and delivered. It has also become desirable and such printing-machines are now required to be provided with a means for associating with each sheet or set of collected or folded sheets one or more whole or part sheets, called "supplements," which supplement sheet or sheets must, as is obvious, be so directed and governed in their travel through the mechanisms that are to deliver them to the main

sheet or sheets, or into the mechanisms controlling the latter, that the supplement-sheet shall register with the main sheet, so that the combined sheets forming the product shall have their margins properly registered. In book or pamphlet work this is particularly requisite, since the succeeding pages brought into juxtaposition by folding the sheets into book form must register to produce perfect work.

The controlling of the position of sheets following each other in rapid succession, either to printing mechanisms, to associating mechanisms, to folding mechanisms, or to delivering mechanisms, is a serious problem, and requires a most sensitive governing mechanism that will automatically and quickly regulate itself, for the reason that where the paper travels at a high rate of speed the slightest inaccuracy of feed will quickly multiply, and therefore soon destroy register, and result in the destruction of work. The present invention provides a mechanism for controlling the operation of the sheet-feeding mechanism that is automatically governed by the passing sheet, so that while a sheet carried onward in the correct position to properly register may pass this controlling mechanism, a sheet that is out of proper position—that is, advanced too much or too little ahead or behind—causes said controlling mechanism to come into action, and so operate the feeding mechanism as to cause the succeeding sheets to assume the correct position of register. Thus the sheets arriving from any cause at the point occupied by this registering mechanism automatically act in passing the same to set into operation the means for correcting the faulty feeding movement, thereby not only preventing the extent to which a sheet may be out of register from multiplying, but acting to cure the cause by restoring the correct position of the mechanisms, or imparting to them an adjustment that will produce proper register.

The embodiment of this invention illustrated by the annexed drawings is a structure particularly designed for attachment to web-printing machines, and as thus embodied will be described, though its adaptation for use with hand and other sheet-feeding means is contemplated.

In said drawings, Figure 1 illustrates by a

side elevation, Fig. 2 by a plan view, Fig. 3 by an end elevation, and Fig. 4 by a longitudinal sectional elevation, a machine provided with my improved registering apparatus. Fig. 5 is an enlarged longitudinal sectional elevation of the sheet-feeding or position-controlling mechanism, of which Fig. 6 is a detail, and Fig. 7 a plan view, showing more particularly the gearing. Fig. 8 represents a front elevation, 10 and Fig. 9 a longitudinal sectional elevation, (both drawn upon an enlarged scale,) of the mechanism for printing, perforating or punching, and winding up a supplement-web. Fig. 10 is an enlarged plan view of the register-15 governing mechanism. Figs. 11, 12, and 13 are enlarged sectional elevations of said register-governing mechanism, showing the same in three different positions of its operations. Figs. 14, 15, and 16 are still more enlarged sectional 20 elevations of said register-governing mechanism, showing three different adjustments of the sheet therewith. Fig. 17 is an enlarged plan view, and Figs. 18, 19, and 20 side elevations, 25 of an electrical apparatus forming part of said register-governing mechanism. Figs 21, 22, 23, 24, and 25 are details of said electrical apparatus. Figs. 26, 27, and 28 illustrate a modified construction of said register-governing mechanism; and Figs. 29, 30, and 31 show such 30 modified apparatus, by much enlarged views of the same, in three positions of operation.

That the purpose and conjoint operation of this register-governing mechanism with the delivery mechanism of a printing-machine may 35 be more readily appreciated, the structure and operation of the devices of said printing-machine and its delivery mechanism will first be explained, and then the co-operation therewith of the register-governing mechanism will be 40 explained. Referring, then, more particularly to Figs. 1 to 4, which are general views, the machine thus represented is one provided with means for operating upon two sets of sheets fed independently to it, and it comprises a 45 means for printing one or both of said webs, as the case may be. It thus embodies here a rotating printing mechanism illustrated by the last type and impression cylinders A B, as well as cylinders C D, provided with cutting mechanisms coacting to divide, perforate, or punch said web. The cylinders A B are provided with toothed wheels 101 102, from which motion may be communicated to the various other 50 rotating devices in proper time and direction through suitable gear-wheels. Thus the cutting-cylinders, which are provided with toothed wheels 104 105, are driven by an intermediate, 106, while the delivery mechanism, which is shown to be a gathering apparatus 55 consisting of a cylinder or carrier, E, and the necessary appurtenances, is set into timely motion by a train of wheels, 107 108 109 110 111 112, the latter of which is fast upon the shaft of said cylinder E, while the former engages 60 with the wheel 104. Sets of sheet-conducting tapes 51 52 lead from the cutting-cylinders C D to the gathering-cylinder E, the set of tapes

51 being stretched from the pulleys 53, thence over pulleys 54, and returned around pulleys 5. The tapes 52 are stretched from pulleys 55 70 and return around pulleys 56. These tapes 51 52 constitute a conveyer carrying the sheets from the cutting-cylinders C D toward the carrier E, and run in contact as far as pulleys 56, the space from which toward the pulleys 54 is 75 spanned by conductors 57, while the space between the pulleys 5 and the cylinder E is provided with a conveyer formed in part by the conductors 58 and tapes 59, which tapes 59 run from the pulleys 54, pass in contact with the 80 lower surface of the cylinder E, and return over pulleys 60 61. A third set of tapes, 62, run from pulleys 63 in contact with the cylinder E and return over pulleys 64 and 65. Between the pulleys 60 and 63 a set of switches, 85 6, are provided, and these switches, together with the tapes 59 62 and conductors 58, form the means for guiding sheets upon said cylinder E and directing them around upon the surface thereof, such switches 6 also acting, when 90 properly rocked, to enter their ends within the peripheral line of the cylinder E as a means for stripping a sheet or collected sheets from the surface of said cylinder, directing the same outward therefrom between the tapes 59 and 95 other tapes, 66 67, the tapes 66 extending outward from the pulleys 68 and the tapes 67 from the pulleys 61, and together constituting a conveyer for delivering the sheets to a piling or other mechanism. These several tapes will be 100 driven with uniform surface speed by motion derived from a toothed wheel, 151, with which the carrier E is provided, through toothed wheels 152, 153, 154, 155, and 156, with which the pulleys 64, 5, 54, 82, and 56 are provided, 105 and wheels 157, 158, and 159, with which the pulleys 63, 68, and 60 are provided. (See Figs. 11 to 13.) No further description of this gathering mechanism need be made, since it is or may be substantially like that described in the 110 Patents Nos. 192,510, 192,954, 193,056, 213,793, and is now a well-known mechanism for rapidly 115 delivering sheets; and it will be understood, therefore, that a web of paper, as 99, may be led from a roll, as 100, through the printing mechanisms and the cutting-cylinders C D, and be severed or partially severed transversely by the latter to divide it into sheets or to define 120 its line of such division, which sheets will be conveyed by the tapes 51 52 to the gathering-cylinder E, and there be collected or associated to any desired number, and by the proper 125 operation of the switches 6 the body of collected or associated sheets be directed in a pack to the tapes 66 67.

The carrier E may of course be provided with suitable mechanisms, and form part of a rotating folding mechanism—such, for instance, as that shown in Patents Nos. 143,674, October 14, 1873, and 171,196, December 14, 1875—or be 130 capacitated to gather as well as fold, as in Patent No. 171,494, May 29, 1877, or have the characteristics of construction shown in No. 192,034, June 12, 1877.

With this machine is shown a means for printing the web 99 and rolling it upon a shaft or core, 1, for use as a supplement-web. (See Figs. 8 and 9.) This mechanism consists 5 of the shaft or core 1, that is mounted removably in bearings in the frame-work, and of the guiding-roller 69, mounted to turn in fixed bearings in the frame-work, and of a guiding-cylinder, 70, which may carry a tympan-cloth 10 to take up the offset and prevent blurring, and a weighted cylinder, 71, which are mounted in swinging arms 72 and driven positively by means of toothed wheels 113 114, and an intermediate, 115, which meshes with the wheel 15 101. The web 99 from the roll 100 will pass through the printing mechanisms and be printed, through the cutting-cylinders C D and be partially severed or punched, as the case may be, and as will be further explained, and then be 20 directed over the roller 69, under the guiding-cylinder 70, around the weighted cylinder 71, and into the shaft or core 1, and be tightly wound upon the latter, so as to form a roll of printed web, as 191, which may be removed 25 from its bearings and mounted upon bearings in the lower part of the frame-work, as is seen at the right-hand lower corner of Figs. 1 and 4. This web may be led from the roll 191 in the latter position, through a feeding and cutting mechanism, and thence to the conveyer constituted in part by the tapes 51 52, that conduct sheets to the gathering or folding cylinder. This feeding apparatus consists principally of the rollers 40 41 42, (see Figs. 5 and 30 6,) the rollers 40 41 of which are shown here to be driven by frictional contact from the roller 42, which latter is provided with a toothed wheel, 116, gearing through an intermediate, 117, with the toothed wheel 118 35 40 on the shaft of the cutting-cylinder 44, which latter wheel is geared with a wheel, 123, by which the cutting-cylinders 43 44 are driven in unison. This shaft of the cylinder 44 is also provided with a toothed wheel, 119, which 45 is driven by a toothed wheel, 120, that is splined upon the shaft 125, said wheel 120 being arranged to be thrown into and out of gear with the wheel 119. 50 On the shaft 125, behind the wheel 120, is a toothed wheel, 124, (shown in dotted lines, Fig. 4,) which gears with the wheel 105, and on the opposite end of the shaft 125 is splined a toothed wheel, 122, that gears with a wheel, 121, fast upon the shaft of the cutting-cylinder 44. 55 This wheel 122 is also arranged to slide upon the shaft 125, so that it may be thrown into and out of gear with the wheel 121. The wheel 120 is but half the diameter of the wheel 119, while the wheels 122 121 are of equal diameter, 60 from which arrangement it will be observed that when the wheel 120 drives the cutting-cylinders 43 44 and the feed-rollers 42 41 40, said mechanisms will move at one-half the speed they will have when driven by the wheels 65 122 121. From these cutting-cylinders 43 44 the supplement-web enters a conducting-pathway formed by the conveying-tapes 59 79.

The tapes 59, heretofore partially described, are extended from the pulleys 61 around pulleys 80, thence pass over the carrier F, constituting in part the sheet-registering mechanism, and thence lead to the pulleys 54. The tapes 79 run from pulleys 81, placed above the pulleys 80, thence pass over the carrier F, run in contact with the pulleys 54, and return 75 over pulleys 82 and bending or stretching pulleys 83 to the pulleys 81.

From this general description and that contained in Letters Patent No. 225,746, it will be understood that the supplement-web, 80 severed into an appropriate sheet in passing the cutting-cylinders 43 44, will be carried to the pathway constituted by the tapes 51 52, so that such supplement-sheet will be associated with a main sheet that is running directly to the 85 delivery mechanism; and it will also appear that the feeding-rollers 40 41, which determine the surface extent of the supplement web or sheet that passes through them for association with this main web or sheet, must govern the 90 relative position of the supplement-sheet with respect to the main sheets; and though the machine shows the mechanisms feeding the supplement-web as being positively driven by the mechanisms that operate upon the main web, 95 still it is a practical impossibility to cause supplement-feeding rollers carrying the sheets by contact of the surfaces to feed a number of sheets successively to the main sheets, so that each of such supplement-sheets will be associated with a main sheet in the required position or adjusted relation thereto, no matter how nice the relative adjustment of the mechanisms may have been made at the beginning 100 of the operation. Thus in practice it is found 105 that either from the stretch of the paper, its varying thickness, or the irregular movement it is given by the frictional contact of the feeding-rollers, which permit an injurious though imperceptible slipping to occur, a means for 110 governing the speed of their feeding action is required, so that the speed at which they shall feed forward the supplement-web may be increased or diminished, as occasion may require, so as to regulate their action when feeding 115 too fast or too slow. The faster or slower action of these feeding-rollers 40 41 may be accomplished in divers ways, as by gear. I prefer, however, to govern their feeding action by increasing or diminishing the diameter 120 of one or both of them, which may also be accomplished in various ways. One mode is shown in an application filed by me June 20, 1881, where a section of the periphery is moved to and from the center by gearing. Rollers 125 made with a radially-moving sectional periphery, said sections actuated in a common manner, as by longitudinally-moved wedges or other cam action, might be used, in which case, as the extent of expansion is comparatively 130 small, the rollers may be driven by gear-wheels having elongated teeth. One method adopted by me is shown upon an enlarged scale in Figs. 5, 6, and 7. These feeding-rollers 40 41 have

their shafts provided with sliding boxes 132 133, whereby said rollers may be adjusted vertically in suitable sockets in the side frame, which bearings are provided with threaded 5 sockets, in which the opposite ends of an adjusting-bolt, 84, enter, said ends of the bolt having right and left screw-threads, so that they may operate to adjust the relation of the peripheries of the rollers 40 41, which are in contact with each other, with such accuracy as to cause such peripheries to nip or frictionally bite the web of paper 99 as may be required to enable them to properly feed it forward. The roller 10 41 is a collapsible and expansible roller, which 15 capacity is given to it by providing it with a metal core, 45, and an india-rubber or other elastic clothing, 46, that will readily compress and expand.

The boxes 131 may form a part of the hangers 20 88 89, and the pulleys 129 130 may be attached to the shaft 96.

The roller 40, which co-operates with the roller 41, will be of metal or other hard substance. Its shaft is carried in hangers 88 89, 25 which have screw-threaded upper ends that travel in threaded nuts, the circular peripheries of which have the form of worm-wheels 92 93. These worm-wheel nuts are supported so as to revolve horizontally by means of hubs 30 which bear between bracket-collars 90 90 91 91. The worm-wheels 92 93 are engaged by worms 94 95, carried by a shaft, 96, that is driven by a wheel, 126, from a pinion, 127, on a shaft, 128, that is provided with belt-pulleys 129 130. 35 When the pulley 129 or 130 is rotated to move the shaft 128 in either direction, it is obvious that through the worms 94 95 and the wheels 92 93 the hangers will be raised or lowered, as the case may be, and thus cause a corresponding 40 movement to be given to the rollers 40 41, the contact of the peripheries of which will be secured by the adjusting-bolt 84. These rollers 40 41 depend upon surface contact for their 45 rotation, and they are driven by the contact of the roller 41 with the roller 42, which latter should be of metal or other hard substance, and is, as before explained, positively driven by the wheel 117. When the adjustment is that shown 50 in Fig. 5, where the roller 41 is shown as enlarged to its greatest dimensions, and therefore having its fullest feeding capacity, the supplement-web 99, passed between the rollers 40 41, will be fed thereby with an onward movement nearly equal to the surface speed of the 55 rollers 40 41 42; but if, from any of the enumerated causes, this feeding movement is found to be too great to cause the supplement-sheet to be correctly associated with the main sheet, and a slower movement of the supplement-web 60 is required, it may be accomplished by so rotating the worm-wheels 92 93 as to cause the same to move the hangers 88 89 downward, and thereby cause the rollers 40 41 to bodily descend and the roller 41 to be forcibly pressed 65 upon the periphery of the roller 42, which operation will result in the compressing of the elastic clothing 46 of the roller 41 between the

hard surface of its core 45 and that of the roller 42, as in Fig. 6. This operation will cause the elastic clothing 46 to be displaced on opposite 70 sides of the center or its point of contact with the roller 42, and though the peripheral or surface speed of the clothing 46 will at such point of contact be equal to that of the driving-roller 42, said clothing will be so far stretched outwardly as to be tantamount to an increase of 75 the peripheral extent of the roller 41, and at the same time to a decrease of the diameter of said roller 41. That portion of the periphery of the roller 41 that is in contact with 80 that of the roller 42 will travel at a uniform speed therewith, either in its collapsed or expanded condition; but it will be observed that though, when collapsed, as in Fig. 6, the stretched or extended portion of its clothing 85 46 will travel at the same surface speed at its point of contact with the roller 42 as such roller has, yet that this clothing 46 will by its elasticity tend to expand as it approaches and to contract as it leaves the point of contact 90 with the roller 42, the result of which is that the periphery of this contracted rubber clothing will be extended on opposite sides of the contact-point with such roller 42, and thus expanded will present a length of surface or peripheral extent that must pass the roller 42 95 that is as much greater than that presented to the roller 40 as the degree of compression provides, and that this length or extent of surface will increase as the compression is increased, and vice versa; further, that such elastic clothing will contract by its own inherent capacity as it approaches its contact-point with the roller 40 to the same extent to which it is expanded in approaching the point of contact with the driving-roller 42; hence it will 100 be apparent that while the extent of its surface passing in contact with the roller 40, to drive the same, will always be the same and uniform, its speed of travel will be slower or faster, according to the degree of compression it is given at the driving-roller 42, for the reasons that it always contracts to its normal condition or size in passing the roller 40, and that its speed will be determined by the length it 105 is given in passing the roller 42, which length must be engaged by the periphery of the driving-roller 42, which is always moving at a given speed, and consequently consume more or less time in passing over the same, as the 110 case may be.

If the adjustment or compression of the roller 41 should be found to feed the supplement-web 99 too slowly, a contrary movement or upward bodily adjustment of the rollers 40 41 may be 115 made to cause the said supplement-web 99 to run faster. In order that this adjustment may not depend upon hand operation, but, on the contrary, be automatic, I have devised a register-governing mechanism which is comprised 120 in part by the carrier F, over which the supplement-sheets travel to the conveyer formed by the tapes 51 52, or it might be to the carrier E, or any other sheet-delivery mechanism to

which a main sheet is regularly forwarded. Before describing this register - governing mechanism it will be advantageous to understand more particularly the mode of preparing the supplement-web for the action of this register-governing apparatus upon or in connection with it.

Referring now to Figs. 8 and 9, which are enlarged views of the supplement printing and winding apparatus heretofore referred to; it will be observed that the blade-carrying cylinder D is provided with a punch, 50, projecting from its surface, with which a recess, 49, provided in the cylinder C, co-operates, and that the result of their conjoint action is to perforate the supplement-web 99 with a series of holes, 20, preferably central, which holes will be the distance of a sheet's length apart, (see Figs. 5 and 7,) said cutting-cylinder C D having a circumference equal to the desired length of the supplement-sheets.

It may be remarked that the cylinder D will also be provided with a socket, 47, for the reception of a cutting-blade, 48, as in Fig. 4, 25 extending the length of said cylinder, and that the cylinder C has a corresponding cutting-slot, 39. (See Fig. 4.) If this blade is made to partially sever the web, it may be used in connection with the punch 50, and when these 30 cutting-cylinders C D are used upon the main web the punch 50 will be omitted, and the cutting-blade may then entirely or only partially sever the web, as the case may require.

Great difficulty is experienced in properly 35 winding up a web of paper upon a shaft or core, as 1, so as to form a tightly-wrapped roll, 191, and this difficulty arises from the fact that the laps of paper constantly accumulating upon said shaft or core constantly increase the size 40 of the roll, so as to raise the weighted laying-cylinder 71, which therefore changes the distance between the source of supply of such web and the point at which it is delivered upon the roll 191, thereby causing a varying tension, 45 which results at frequent periods in the rupture of the web. The peculiar mechanism I have devised, and which is shown best in Fig. 9, avoids this faulty operation, for the reason that as the cylinders 70 71 are carried upward 50 by the constantly-increasing roll 191, as shown by dotted lines, they are caused to approach the roller 69, which is a fixed point of travel for the web, and so take up the web as to keep it evenly stretched over them during the entire increase in the size of the roll 191, thus 55 preserving an even tension and tightly winding or laying the laps upon each other to form the constantly-increasing roll of wound paper.

It will be apparent that the printed supplement-web punched in passing through the cutting-cylinders C D will be wound up in a roll, as 191, on the shaft or core 1, and that when this supplement-web is led through the feeding-cylinders 40 41 the central holes, 20, with 65 which it is provided, will mark or define the point of severance between succeeding sheets, which holes 20 become the index showing

whether or not said supplement-sheets are properly severed transversely, as in Fig. 7, or partially so severed, in passing between the cutting-cylinders 43 44, to produce proper sheets for association with the main sheets. It will now appear that the supplement-web 99 will be controlled by the feeding-cylinders 40 41, so that it will enter between the cutting-cylinders 43 44 and be properly severed or partially severed into sheets, which will be carried by the conveying-tapes 79 59 onto the carrier F, over the surface of which such sheet passes to the main sheet, and that the two sheets brought together in the conveyer consisting of the tapes 51 52 will thereafter travel together to be gathered, folded, or otherwise delivered.

The carrier F is provided with mechanisms rendering it capable of determining when the sheet passing over its surface is in proper position or out of proper position, and of adjusting the feeding-rollers 40 41, so that the latter may properly act to correct the faulty feeding of the supplement - web 99. These mechanisms are constructed and arranged as follows, (see Figs. 10 to 20.)

The carrier F is provided with an electrical circuit closer and breaker, 9, constructed in form of an arm projecting from a rock-shaft, 21, that is journaled in the heads of the carrier F, so as to be capable of a movement with respect to the surface of the carrier F substantially like the ordinary gripper movement 100 of a cylinder printing-machine—that is to say, said closer and breaker may be closed down onto the periphery of the carrier F during each or alternate revolution thereof, so as to engage the leading edge of the sheet in manner as 105 does such grippers, and this shaft may also carry ordinary grippers. The shaft 21 of this closer and breaker is provided at one end with a rock-arm, 22, the stud or roller of which bears upon a cam, 75, fixed to the frame-work, 110 the operation of which cam is to open the closer and breaker during each revolution of the carrier F. On the opposite end of this rock-shaft 21 is provided a collar, 18, the periphery of which is provided with countersunk portions, (see Fig. 13,) in which the friction-roller 16, at one end of a two-armed lever pivoted to the cylinder-head, engages to hold the breaker and closer 9 in its open or closed position, as the case may be, said two-armed lever having its end 17 spring-seated, so as to 115 constantly press the friction-roller 16 to duty. It will thus appear that at each revolution of the carrier F the closer and breaker 9 is opened and stands open. The closing of the closer 120 and breaker 9 is performed by an outside cam, 36. (See Figs. 10 to 13.) If the carrier F is to receive a sheet at each of its revolutions, its closer and breaker would require to be closed during each revolution, and therefore in that 125 case the cam 36 might be a fixed cam; but as it is desirable that the breaker and closer 9 shall at times operate only at each second revolution of the carrier F, as will hereinafter ap-

pear, this cam 36 is pivoted to the framework and provided with means for vibrating it, so that its operative lower end will be engaged by the rock-arm 22 at each second revolution only of the carrier F. For this purpose it is provided with a spring, 19, which operates to throw its operative end outwardly or away from the rock-arm 22, and its tail end, 103, is extended so as to be engaged by a cam, 146, that is fast upon the shaft 147 of the wheel 111, (see Fig. 1,) from the size and relation of which gearing it will be observed that the shaft 147, making one turn to every two of the carrier F, which is driven by the wheel 110, thereby causes this cam 36 to be vibrated at each second revolution of said carrier. If it is desired that this cam 36 shall operate at every revolution of the carrier F, it is only necessary to vibrate it to the position shown in Fig. 12, and to secure it there by the set-screw 148. This closer and breaker 9 is provided with an electrical conducting-wire, 10, that passes through holes provided for it in said closer and breaker, being branched so as to present two contact points at the face of said closer and breaker. This wire 10 is coiled two or more times about the shaft 21, and will be insulated by a rubber or other suitable coating at points of its contact with said closer and breaker and with its shaft 21, and proper portions of its exterior surface will be exposed to receive the end of a spring-tongue, 11, that is secured to the inner periphery of the carrier F by an insulated screw. The forward end of the tongue is spring-like in character, so that it will maintain a conducting-contact with the exposed surface of the coils of wire 10 during the vibratory movements of the closer and breaker 9. From the heel of this tongue 11 a conducting-wire, 12, is entered into a channel provided therefor in the shaft 38 of the carrier, and carried to a point outside of the framework where it is again brought to the surface, of said shaft and terminated in a coil, 12, wrapped about the periphery thereof. This coil is provided with a naked exterior surface, upon which the free end of a spring-tongue, 13, bears, so as to preserve conducting-contact therewith during the entire rotation of said shaft 38. This tongue 13 projects from an insulated post, 85, from which post the wire 12 is extended to connect with one of the coils, 97, of a magnet, I, the other coil, 98, of this magnet being connected with the positive pole of the battery x by a wire, 33.

The carrier F is provided with a second conducting-wire, 23, that is entered through an opening in the shell of the carrier F, in which it is properly insulated, so as to present one or more naked ends situated at a proper point to have contact with the ends of the wire 10 in the closer and breaker 9 when the latter is closed down upon the periphery of the carrier F. This wire 23 is preferably elastically supported in a spring-arm, 24, properly insulated, the operation of which will be to press the ends of the wire outward

from the periphery of the carrier F far enough to insure contact with the wire 10, and to give sufficiently to accommodate the closing movement of the closer and breaker 9. This wire 23 is connected with a post, 25, for a purpose yet to be explained, and from thence enters within the shaft 38, from which shaft it emerges outside of the frame at a point adjacent to that from which the wire 12 is brought to the surface of said shaft, and, like it, is wound in a coil upon the exterior of such shaft, upon the naked outer surface of which coil a spring-tongue, 14, bears. This tongue projects from an insulated post, 86, which post is connected by the wire 23 with the negative pole of the battery x. It will thus be observed that when the closer and breaker 9 is vibrated, so as to bring this wire 12 into contact with the wire 23, a perfect circuit from the battery x through such wires, through the magnet I, to the battery x will be made, and consequently that the coils of the magnet I will be charged, and thus cause the heel of the armature 76 to be drawn down, in which position it will be held with its outer end elevated, as in Fig. 18, as long as said circuit is established. The armature 77 of another magnet, J, may be operated by an electrical circuit established through the magnet J by the following mechanisms:

The carrier F is provided with an arm, 73, (see Figs. 14, 16,) pivoted at a point near the circuit closer and breaker 9, and extending forward so as to play in a recess in the periphery of said carrier. This arm 73 is provided with a bearer, 7, near its pivot, and at its forward end with an insulator-button, 8, which may be engaged by a second arm, 74, that is fast to the insulated post 25, which arm 74 is of spring-like character, so that it normally projects outward, and thus holds the arm 73 in its outermost position, the arm 74 being provided at its end with an insulator-button, 4, which forms a rest for it against the inner periphery of the carrier F. The post 25 is connected through the wire 23 with the negative pole of the battery x, and when the arm 74 is depressed, as will be explained, it is connected with the positive pole of the battery x by means of an insulated post, 37, by a wire, 35, that passes through the shaft 38 and terminates in a coil, 35, on said shaft, near the coils 23 12, which coil 35, like them, is insulated upon said shaft and provided with a naked surface, upon which a spring-tongue, 15, bears, the latter, through an insulated post, 87, being connected by a continuation of the wire 35 with the coil 30 of a magnet, J, the other coil, 31, of said magnet being connected to the wire 33. It will now be apparent that when the closer and breaker 9 is vibrated onto the periphery of the carrier F the rear end of its face may, when the paper is between it and the projection or bearer 7, so press upon the lever 73 as to cause its inward vibration, and through its forward end a like movement of the lever 74, the forward end of which will be brought into electrical contact with the post 37, and thus

establish an electrical circuit from the battery *x* through the magnet *J*, and thence through the wire 35, post 37, arm 74, post 25, and wire 23, to the negative pole of the battery *x*, which 5 electrical circuit will cause the magnet *J* to draw down the heel of the armature 77, and thus cause the forward end of such armature to remain elevated as long as such circuit is established.

10 The armatures 76 77 co-operate with clutch mechanisms supported upon the shaft 38 of the carrier *F*, whereby the motion of said shaft may be communicated to the grooved belt-pulleys 134 135, that turn freely upon the shaft 38, 15 and which pulleys are belted, respectively, to the pulleys 129 130 on the short shaft 128. (See Fig. 7.) The clutching mechanisms belonging to each of these pulleys are alike in construction, and therefore a description of 20 one will be sufficient to explain them. (See Figs. 17 to 20.) Each of these pulleys 134 135 is secured to a hub, 136, that carries a ratchet-wheel, 26, with which ratchet-wheel engages a dog or clutch, 27, that is carried on a stud 25 secured to a disk, 138, that is splined upon the shaft 38, so as to constantly revolve, said dog being held in either its outward or inward position of adjustment by means of a spring, 139, which bears laterally against it.

30 The ends of the armatures 76 77 are T-shaped, which provides them with projections 3 and *i*. The projections *i* enter a guiding-groove, *a*, formed in the side of the pulleys 134 and 135, whereby said armatures are prevented from 35 displacement. The projections 3 are beveled on their rear faces, and the end of the dog 27 has a lateral projection, 2, at its side, which is beveled in a contrary direction, so that when the rearward end of the armature is drawn 40 down by the magnet and the forward end raised, as in Fig. 18, the dog 27 will be depressed or thrown inwardly by the action of its projection 2, passing in contact with the under side of the projection 3 of the armature, the dog being thus 45 depressed or thrown inwardly to engage with the teeth of the ratchet 26, where it will be held by the lateral pressure of the spring 139. Thus engaged or clutched with the ratchet 26, this disk 138, constantly revolving, will carry with 50 it such ratchet-wheel 26, and consequently will cause the pulley 134 to revolve. When, however, the outer end of the armature 76 or 77 is depressed, as in Fig. 20, the beveled lower face of the projection 2 of the ratchet will ride over 55 the beveled upper face of the projection 3 of the armature, and thereby cause the dog 27 to be raised or thrown outward, thereby being disconnected or unclutched from the ratchet-wheel 26, whereupon the disk 138 will revolve 60 freely, while the ratchet-wheel 26 and the pulley 134, to which it is attached, will have their motion suspended. These pulleys 134 135 being provided with a precisely similar clutching mechanism, as the duplication of letters of reference indicate, it is apparent that one or the other 65 may be clutched to the shaft 38 at varying periods, and consequently be revolved with said

shaft, and as these pulleys are connected with the pulleys 129 130 by belts 140 141, it will also appear that their rotative motion will be communicated to this shaft 128, and as the belt 141 will be crossed, the motion communicated by one pulley will be contrary to that communicated by the other. Thus when the pulley 134 is set into rotation it will turn the pulley 75 129 in its own direction, and thus cause the shaft 128, through the worms 94 95 and the mechanism connected therewith, to lower the feed-rollers 40 41, the latter be compressed, and a slower feeding action thereof to ensue, and that when 80 the pulley 135 is set in motion it will turn the pulley 130 in a direction contrary to its own motion by reason of the crossed belt, and thus rotate the shaft 128 in such a direction as to cause the feeding-rollers 40 41 to be raised, thus 85 allowing the roller 41 to expand and the faster feeding action of said rollers to take place.

Referring now to Figs. 14 to 16, it will be understood that if a sheet of paper has been properly fed to the carrier *F*, or so that its forward end is in the proper position to register with a main sheet when it reaches the same, and that if that position is one that said feeding edge just covers the point occupied by the conducting-wire 23 and operating as an 95 insulator or non-conductor, preventing contact of the wires 10 and 23, which would establish the electrical circuit heretofore described, said sheet will be carried onward and delivered from the carrier *F* without affecting 100 the clutching of either of the pulleys 134 135 with the shaft 38; but if for any cause the leading edge of such sheet should not be advanced far enough upon the carrier *F* to insulate the wire 23 or prevent contact of the wire 10 therewith, as in Fig. 15, said wires will be brought 105 into contact and establish an electrical circuit from the battery through the magnet *I*, which magnet will operate the armature 76 so as to carry its forward end into the raised position 110 shown in Fig. 18, in which position it will engage the dog 27 and depress the same or carry it into engagement with the ratchet-wheel 26, thereby setting the pulley 134 into rotation, which, through its belt 140, will rotate the pulley 129, the latter, through its shaft 128 and the connecting-gearing heretofore described, raising the hangers 88 89, which permits the roller 41 to expand, and thus feed the supplement-web 99 onward at an increased speed, advancing 115 the web a little faster and producing slack paper of sufficient extent to produce proper register as it is taken up by the accelerating-tapes 59 79 and advanced to the carrier *F*. When the sheets fed to the carrier *F* reach 120 their proper position, as in Fig. 14, the electrical circuit will be broken and the spring 160 of the armature 76 will depress its forward end, as in Fig. 20, and thereby cause it to throw the dog 27 upward and disconnect it from the 130 ratchet 26, whereupon the motion of the pulley 134 will be suspended and the adjusted position of the rollers 40 41 continue. If, now, from any cause, the sheets passing onto the car-

rier F are advanced too far, when they would obviously prevent the establishment of the circuit through the wires 10 23, and yet be out of proper position, their leading edge will, however, be entered over the projection 7 of the bar 73, and thus cause the face of the closer and breaker 9 to press upon the paper and said projection with a force sufficient to depress said arm 73 on the arm 74, thereby causing the circuit to be established through the arm 74 and wire 35 and through the post 25 and the wire 23, whereby the magnet J will be caused to operate the armature 77, raise its forward end, as is that of the armature 76 in Fig. 18, and throw the dog 27 into engagement with the ratchet 26 of the pulley 35, thus rotating said pulley and communicating its motion in a reversed direction to the pulley 130, which will so turn the shaft 128 as to operate the mechanisms connecting it with the hangers 88 89 and lower the same, and with them the feeding-rollers 40 41, whereby the roller 41 will be pressed upon the roller 42, as in Fig. 6, and thus cause the supplement-web 99 to be fed more slowly onward until the sheets assume a proper position for their leading edges to simply prevent the forming of the electrical circuit between the wires 10 and 23, as in Fig. 14, the circuit operating the armature 77 being broken as soon as the leading edge of the paper fails to be interposed between the face of the breaker and closer 9 and the projection 7, whereupon the spring attached to the armature 77 causes the forward end of the same to be depressed, as is that of the armature 76 as in Fig. 20, and the dog to be thrown out of engagement with the ratchet 26.

From the foregoing description of the operation of this register mechanism it is apparent that if the web breaks, so that no supplement-sheets pass onto the carrier F, the circuits passing through the magnets I J will both be established, the result of which will be that both ratchets will be engaged and both pulleys set in rotation, from which will result an injurious operation of the machine. I have therefore arranged a means for cutting off the supply of electricity to the magnets I J, which throws their armatures and the clutches with which they co-operate out of action. This is accomplished, as is shown in Figs. 21 to 25, by conducting the electricity to said magnets through an automatic switch. This switch is composed of a standard, 142, to which the wire 33 leads directly from the positive pole of the battery, beneath the curved end of which standard 142 is arranged a vibrating arm, 143, that is pivoted to a standard, 145, from which a conducting-wire, 34, communicates with the coils 31 98 of the magnets. It will be apparent from this description that when the arm 143 is raised in contact with the standard 142 the current of electricity may pass from the battery through the wire 33 to the magnets through the wire 34. The standard 142 and the arm 143 are magnetized, so as to convert them into permanent magnets, whereby when they are brought

into contact such contact will be maintained until it is forcibly broken.

The arm 143 is provided with a pin, 78, projecting from its end, which passes through an elongated hole of a bridge-lever, 144, the opposite ends of which are entered into the holes of the armatures 76 77. When the standard 142 and the arm 143 are in conducting-contact, as in Fig. 22, and the register-governing mechanism is in operation, it is obvious that if the current is established so as to pass through the coils 97 98 of the magnet I, to raise the outer end of the armature 76, the heel of said armature will rock the bridge-lever 144 downward without separating the arm 143 from the standard 142, as in Fig. 23, and that a like movement of the armature 77 may take place in the same manner. If, however, both circuits should be established, as in the absence of a sheet upon the carrier F, both magnets will simultaneously operate and draw down both armatures, as in Fig. 24, the result of which will be to cause the bridge-bar 144 to descend and carry with it through the pins 78 the arm 143, the end of which will thus be removed from contact with the standard 142, and thereby switch or cut off the current from the battery through said standard, thus isolating the battery and preventing any further operation of electricity through the devices supported by the carrier F. This causes the feeding-rollers 40 41 to remain in the position occupied by them at the time of the breaking of the web. It is therefore evident that the battery-connection with the magnets via the arm 143 will be maintained through every movement of the armatures, except only when they are both simultaneously drawn down by their respective magnets. When the machine is again ready to operate, the battery may be thrown into communication with the register mechanism by raising the arm 143 into contact with the standard 142, when the register-governing mechanism will operate as hereinbefore described.

It will now be understood that if each main sheet carried onward for delivery requires to have associated with it a supplement-sheet, say, of equal lengthwise dimensions, the supplement-introducing apparatus will be driven by throwing the wheel 122 into gear with the wheel 121, whereby the supplement-sheet fed onward for association with the main sheet will be carried at the same surface speed of the former. The carrier F will then have the cam 36 fixed in the position shown in Fig. 12, so that it will close the closer and breaker 9 at each revolution of said carrier; hence as the carrier F makes turn for turn with the cutting-cylinders 43 44, it is obvious that such supplement-sheets will be regularly carried forward for association with the main sheet, and their relation thereto be governed and determined by the registering apparatus heretofore described.

If, now, it is desired to collect two main sheets together by the gathering apparatus of

the cylinder E, and to deliver a supplement-sheet for association therewith, the supplement-feeding mechanism will be driven by throwing the wheel 120 into gear with the wheel 119, so as to cause the same to run at half the speed of the main-sheet conveying apparatus, and to cause the cam 36 to be operated upon the cam 146 by releasing the holding-screw 148. The operation will then be as

10 follows: While the first main sheet is being fed onward to the carrier E the supplement-sheet will not have passed upon the carrier F, and the closer and breaker 9 thereof will be allowed to stand open during such revolution of it; but 15 as the second main sheet is passing toward the carrier E the cam 36 will be vibrated to operate the closer and breaker 9, and thus bring into operation the register-governing mechanism. A similar appropriate arrangement may 20 be made to collect more than two main sheets and associate with them one supplement-sheet.

It will be observed that the carriers E and F run turn for turn, and that the gearing is so proportioned that the carrier E runs slightly 25 faster than the cutting-cylinders C D, and that the carrier F runs slightly faster than the cutting-cylinders 43 44. This is for the purpose of separating the webs upon their lines of partial severance, or advancing them when the web 30 is entirely severed, so as to provide a slight working distance between sheet and sheet. By providing the cutting-cylinders 43 44 with another, one or more sets of cutting devices, and with such change-gearing connecting the supplement-feeding mechanisms with the main-web-carrying mechanism, and by providing the cam 36 with a proper movement, supplement-sheets one-third, one-quarter, and so on, the length of the main sheet may be registered 35 and associated with such main sheet.

It has been intimated herein that the means of expanding and contracting the supplement-web-feeding rollers 40 41 might have substituted for them other mechanisms accomplishing the operation of increasing and diminishing their feeding action. It is therefore to be understood that any feeding roller or rollers capacitated to perform these functions upon the supplement web or sheets are broadly comprised within the combinations hereinafter claimed. So, too, the carrier F may be provided with other constructions of circuit making and breaking devices, which are governed by the presence or absence of the passing sheet. 50 One form thereof is shown in Figs. 26 to 31. Here the closer and breaker 9 finds its equivalent in the spring-arm 28, and the arm 74 its equivalent in the spring-arm 29, while the wire 23, communicating with the negative pole of the battery, finds its equivalent in the guard 32, to more particularly illustrate which the conducting-wires leading from these devices are marked with the same numbers they have been given in other views.

60 65 It will be observed that the arms 28 29 have a spring-like motion, whereby they constantly press outward from the periphery of the car-

rier through holes therein, and that consequently when such movement of them is not prevented they will have contact with the surface of the guard 32, and therefore establish the currents which will move the armatures 76 77. If the sheet is properly fed, so that its forward edge overlies the arm 28 and its rear end overlies the arm 29, as in Fig. 29, it prevents these arms from having contact with the guard 32 in passing the same. When this is the position of the sheet it will properly register with the main sheet to which it is to be fed and associated. If, however, the sheet has 80 traveled so far onward that its forward end protrudes beyond the arm 28, though it may overlie the same, the tail of the sheet will be so far advanced as to completely expose the arm 29, as in Fig. 30, which will then establish 85 the circuit through the guard 32, and cause the armature to set the clutch mechanism into action, and cause the feeding-rollers to be actuated to feed more slowly. Again, if the action of the feeding-rollers becomes such as to 90 feed the sheets onward too slowly, so that the leading edge of a sheet does not overlie the arm 28, said arm will set the clutch mechanism into proper action to actuate the feeding-rollers so that they will advance the sheets 95 more rapidly. It will thus appear that unless the passing sheet is in proper position, one of these arms 28 29 will have contact with the guard 32, and thus set into operation one or the other clutch mechanism, whereby the action of the feeding-rollers is controlled, and that if the web breaks, so that no sheet passes onto the carrier E, the action of the clutch mechanisms will be suspended, as before described.

100 105 The arms 28 29, separated a distance apart, are capable of acting upon sheets having a time-space between them, and to more accurately operate upon such should be made adjustable with relation to each other. Both of these features are, however, to be made the subject-matter of another application.

Although, for convenience of explaining the invention, a clutching mechanism of peculiar construction has been shown and explained, it 110 115 will be apparent that various forms of clutching mechanism may be employed that may be set into action by the elevation and depression of the armature 76 and 77, and operate to move one or the other of the pulleys 134 135 in the 120 proper direction to effect the adjustment of the feeding-rollers hereinbefore described, one modified form of which is shown in a companion application. A clutching mechanism performing this function is therefore to be understood as embraced in the claims hereinafter made, in which the element of clutching mechanism is expressed.

125 130 It is manifest that the circuit making and breaking devices may be arranged so as to reciprocate and be controlled in their electric contact by the sheet of paper; but such a mode of operation would greatly abridge the time during which they may travel with the sheet

and modify the speed of operation because of their retracting movement; and though such a modification is within the scope of this invention, it will be manifest to those acquainted 5 with this class of mechanisms, which must run at high rates of speed, that such a construction is less practicable than the ones herein illustrated and explained.

When the delivery-carrier E runs with a surface speed equal to that of the printing mechanism, as it may, whether it gathers, folds, both gathers and folds, or simply carries the sheets onward, such sheets will follow each other with little or no space between them. 10 In that case the carrier F will have a corresponding speed, and when the supplement-sheets are of the length of a whole sheet they, too, will run with their edges close together; hence the punch-holes 20 will remove portions of the sheet to provide a working-space for the closer and breaker 9 or arms 28 29.

Although the cylinders 43 44 have been alluded to as cutting-cylinders, because, as shown, they are provided with a severing or partial-severing blade, 170, and a cutting-slot, 180, it should be understood that they may be simple lead-rollers or be entirely omitted. In the organization shown they are supposed to partially sever the web 99 on a line passing through 25 the punched hole 20, which, when separated, produces the result shown in Fig. 7. If the leading end of the web is not carried forward at an increased speed to cause such separation, these cylinders might entirely sever the web; 30 but in that case conductors would bridge the space between said cylinders and the pulleys 35 80 81. If, however, the supplement-web, whether punched or not with the holes 20, be perforated from edge to edge on its dividing-lines by means of a suitable cutter in the cylinder D, as said web is printed and wound up, these cylinders 43 44 might be without cutting instrumentalities in one case, and in another have breaking devices substituted for its cutting devices. 45

The supplement-feeding cylinders may be non-expansible, as shown in my supplement-mechanism patent, No. 225,746, dated March 23, 1880, the position of the supplement-sheet 50 being regulated by the tension on the shaft carrying the printed roll of supplement-web, in which case the electric mechanism may be arranged so that the devices which are herein shown as operating to raise or depress the feeding-cylinders shall operate to tighten or loosen the friction-strap, and thus increase or diminish the tension on the shaft carrying the supplement-roll of printed web, and thereby retard the sheet or permit the same to be advanced, as described in said patent. 60

Although in making one circuit two levers, as 73 74, are called into action, it will be readily apparent that one lever may be made to extend from the breaker or closer 9 to the button 65 communicating through the wire 35 with the opposite pole of the battery.

It will be manifest that any form of gearing—

as toothed or friction wheels—may communicate the motion of the disks 138 or pulleys 134 135 to the mechanism raising and lowering the moving members of the feeding-rollers, and that any other common or equivalent mechanism for adjusting said feeding-rollers may be employed.

This register-governing apparatus has been described as operating to control the position of the supplement-sheets fed onward for association with main sheets that have been provided, and which then simply require to be delivered from the machine, either by a folding or other operation. It is contemplated, however, to combine this register-governing apparatus with a printing mechanism solely, whereby a web printed upon one side, or thus printed and perforated from edge to edge on its line of ultimate division into sheets, or simply punched with holes at such division-points, may be used with a printing mechanism adapted to print its plain side, and the web or sheets detached from such web be so accurately carried to the printing mechanism as to receive their second impression in exact register with their first impression. This will enable "patent insides" now produced in sheet form to be prepared in the web form as rolls, (which is the acceptable mode of transporting paper,) and to be perfected in the most rapid manner upon rotary printing-machines. A practical embodiment of such arrangement will form the subject-matter of another application.

What is claimed is—

1. The combination, with a main-sheet-carrying mechanism and a mechanism for feeding a supplement-sheet thereto, of a register-governing mechanism provided with an electric-circuit maker and breaker the operation of which is controlled by the said supplement-sheet, all substantially as described.

2. The combination, with a main-sheet-carrying mechanism and a mechanism for feeding a supplement-sheet thereto, of a register-determining apparatus consisting of a rotating or traveling electric-circuit maker and breaker that is controlled in its operation by the presence or absence of the supplement-sheet in contact therewith, all substantially as described.

3. The combination, with a main-sheet-carrying mechanism and a mechanism for feeding a supplement-sheet thereto, of a register-determining apparatus consisting of a traveling electric-circuit maker and breaker controlled by the supplement-sheet, and a mechanism that is set into action by said circuit maker and breaker to diminish or increase the speed of said feeding mechanism, all substantially as described.

4. The combination, with a main-sheet-carrying mechanism, of a mechanism for feeding supplement-sheets thereto, consisting of a pair of rollers or cylinders and means for increasing or diminishing their feeding action to accelerate or retard the movement of the paper, all substantially as described.

5. The combination, with a main-sheet-car-

- rying mechanism and means for feeding supplement-sheets thereto, consisting of expanding and retracting rollers or cylinders, of a register-determining apparatus consisting of 5 a traveling electric-circuit maker and breaker that is controlled by the passing supplement-sheets, armatures operated by the electric circuits established and broken, direct and reversing pulleys operated by said armatures, 10 and means transmitting the movements of said pulleys to means for contracting and expanding the circumferential extent of said feeding-rollers, all substantially as described.
6. The combination, with a main-sheet-carrying mechanism and a mechanism for feeding supplement-sheets thereto, of a register-governing mechanism interposed between said sheet carrying and feeding mechanisms, all substantially as described.
- 15 7. The combination, with a main-sheet-carrying mechanism, of mechanism for feeding a supplement-web, mechanism for severing, partially severing, or breaking the same into short lengths or sheets, a register-determining mechanism provided with an electric-circuit maker and breaker the action of which is controlled by the supplement-sheet, and mechanism set into action by the electric circuit and operating to impart a faster or slower movement to 20 said feeding mechanism, all substantially as described.
8. The combination, with a main-sheet-carrying mechanism and a mechanism for feeding a supplement-sheet thereto, of a register-governing mechanism consisting of a traveling electric-circuit maker and breaker that is controlled in its operation by the presence or absence of a sheet in contact therewith, of change-gearing whereby the speed of the supplement-feeding mechanism relative to that of the main-sheet-carrying mechanism is varied to suit its action when short supplement-sheets or a number less than that of the main sheets are fed, and of a cam-arm, as 36, correspondingly operated to produce appropriate vibrations of the circuit maker and breaker, all substantially as 25 described.
9. The combination, with a main-sheet-carrying mechanism and a mechanism for feeding a supplement-sheet thereto, of a sheet-register-determining apparatus consisting of a vibrating circuit maker and breaker, as 9, 28, or 29, supported in a moving carrier, an electric conductor connecting said circuit maker and breaker with one pole of a battery, and a co-operating contact-surface connected with the opposite pole of the battery, the construction being such that sheets while upon and traveling with said carrier may be interposed 30 between said circuit maker and breaker and its contact-surface and prevent the establishing of an electrical circuit, all substantially as described.
10. The combination of a vibrating circuit maker and breaker, as 9, 28, or 29, supported in a moving carrier over which the sheet is led, an electric conductor connecting said circuit

maker and breaker with one pole of a battery, a co-operating contact-surface connected with the opposite pole of the battery, magnet-coils 70 through which the circuit, when established, shall pass, and armatures operated to set the sheet-feed-controlling mechanism into operation, substantially as described.

11. The combination, with a main-sheet-carrying mechanism, a mechanism for feeding a supplement-sheet thereto, and an electric register-governing mechanism controlled by said supplement-sheet, and constructed so as to establish circuits operating two armatures that 75 set into operation two clutches producing opposite movements in the mechanism adjusting the feeding action, of a switch mechanism operating to cut out the battery when both circuits are established, all substantially as described. 80

12. The combination, with a main-sheet-carrying mechanism and a mechanism for feeding a supplement-sheet thereto, of a sheet-register-determining mechanism consisting of a rotating carrier, as F, a single vibrating electric- 90 circuit maker and breaker connected by a conductor with one pole of a battery, and coacting contact-surface, as the wire 23, connected with the opposite pole of the battery, said maker and breaker and contact-surface being attached to the carrier F, all substantially as described. 95

13. The combination, with the carrier, as F, of the vibrating electric-circuit maker and breaker, as 9, and the co-operating elastically- 100 seated contact-wire 23, which wire and breaker are supported by the carrier F, substantially as described.

14. The combination, with the carrier, as F, and its vibrating electric-circuit maker and breaker 9, of the coacting conducting-wire 35, and connecting lever or levers operated by said maker and breaker to establish the electric circuit, substantially as described.

15. The combination, with the carrier F, and its means controlled by the presence or absence of the sheet for establishing an electrical circuit, of a suitable battery, two magnets, as I, J, their armatures, as 76 77, clutching mechanisms operated by the latter to set pulleys 110 134 135 into motion, and gearing for communicating their motion to the mechanism operating to adjust the feeding-rollers, all substantially as described.

16. A web-winding apparatus consisting of 120 a core or mandrel, a weighted cylinder, as 71, and a guiding-cylinder, as 70, all hung in swinging arms, and a guiding-roller, as 69, hung in stationary bearings, substantially as described.

17. The combination, with a loosely-journaled band-pulley, as 134, and an armature having a projection, as 3, of a driving-disk, as 138, and a clutch-dog, as 27, having a projection, as 2, substantially as described. 125

18. The combination of disk 138, ratchet 26, dog 27, pulley 134, and magnet, as I, substantially as described.

19. The combination, with a main-sheet-car-

rying mechanism and a mechanism for feeding supplement-sheets thereto, of a carrier, as F, and its spring-raised circuit closer and breaker 9, and the adjustable cam 36, substantially as described.

5. 20. The combination, with feeding cylinders or rollers provided with automatically-operating means for governing or regulating their feeding action, of cutting devices, all substantially as described.

In testimony whereof I have hereunto set my hand in the presence of two subscribing witnesses.

LUTHER C. CROWELL.
